UNITED STATES PATENT OFFICE

1,925,831

STORM SASH HOLDER AND LOCK

John Christian, Milwaukee, Wis.

Application March 20, 1931. Serial No. 523,959

1 Claim. (Cl. 292—263)

My invention resides in a device designed for use as a storm sash holder, and embodies in its construction means for supporting the storm sash in its open position, and also means for locking the storm sash in its closed position.

Means are also provided for maintaining the storm sash in partially open position, and locked in such position, to permit ventilation, as at night, of the room from which the window opens.

Simple means of support and attachment have been provided, whereby the storm sash may easily be removed from its position of association with the window, when seasonal requirement has ended, and storage is desirable.

Having thus outlined the nature and purposes of my invention, I will now describe the construction shown, and in the appended claim will point out the novel features of my invention.

In the accompanying drawing:

Figure 1 is a transverse vertical sectional view through a window casing, and showing the application of my invention.

Fig. 2 is a fragmentary view, on the scale of Fig. 1, showing how the storm sash is maintained in its open position.

Fig. 3 is a like view showing how the storm sash is locked in its closed position.

Fig. 4 is an enlarged view, looking from the inside of the window, showing details of the construction and arrangement of my device.

Fig. 5 is a horizontal sectional view on the line 5—5, Fig. 4, looking in the direction of the arrows, with some elements shown in plan.

Fig. 6 is a view in side elevation of the anchor plate, as in fixed position upon the blind stop of the window frame.

In the drawing, the letter A, Fig. 1, indicates a window assembly of any approved construction, in which the top face plate is indicated by the numeral 10, and the blind stop by the numeral 11. The storm sash 12 has a hooked, pivotal connection, as at 13, between its upper cross rail and the plate 10, and, when in its closed position, is adapted to lie flat against the blind stop.

Near the lower end of each of the opposite blind stops, an anchor plate 14 is permanently attached by means of screws 15, passed through perforations in the anchor plate, and entered into the blind stop. The anchor plate 14 is slotted laterally from its inner edge, as at 16, and is counterbored at the end of the slot, to provide a circular recess 17 on its inner side, for a purpose which later will be described. A channel 18, is cut partly across the face of the

blind stop, underlying the anchor plate, and registering with the slot 16 and the circular recess 17 therein.

One flange of an angular bracket 19 is attached to each outer stile 20 of the storm sash 12, by means of screws 21 passed through perforations in the flange and into the stile, such attachment being designed to remain undisturbed in the subsequent handling of the storm sash. The other flange of the bracket 19 is perforated for the reception of a pivot pin in the form of a rivet 22, between the head of which and the flange is disposed a lock washer.

The point of the rivet 22 is also passed through a perforation in the outer end of one member 23 of a toggle, and such point is upset so as to pivotally connect the parts with a yielding frictional engagement, due to the resiliency of the lock washer. The other end of the toggle member 23 is joined to the corresponding end of the second toggle member 24, by means of a pivot of peculiar construction, which later will be described. A headed stud 25 is fixed in the outer end of the second toggle member 24, the pivot 22 and the stud 25 being in axial alignment, when the storm sash is closed.

The meeting ends of the toggle members 23 and 24 are connected by a bolt 26, the reducing shank of which is passed through aligned perforations in such meeting ends, and through intermediate washers, which are spaced from each other by a locking washer. In order to make a more stable connection, it is desirable that the aligned perforation in the member 23, be threaded to receive the threaded end of the bolt 26, on which the nut 27 may jam so as to hold the adjustment. The lock washer permits the toggle members to pivot on the bolt 26 with a yielding frictional contact. The head of the bolt 26 is elongated so as to constitute a crank handle, by means of which the toggle may be rotated about the aligned pivotal points 22 and 25, when the storm sash is in its closed position.

A spring acting expansively is confined between the head of the stud 25 and the side of the toggle member 24. In the drawing, I have shown a blade spring 28, attached at one end to the toggle member 24, and provided at its free end with a perforation through which the stud 25 is passed; but any type of spring may be used for the purpose.

With the storm sash supported upon the hooks 13, the shank of the stud 25 may be passed into the slot 16 by compressing the spring 28 against the anchor plate, and the head of the stud

- entered in the circular recess 17. The spring 28 then acts to prevent accidental disengagement of the head of the stud from the recess.
- The toggle member 24 is provided at its inner 5 end with an offset finger 29, which overlies the corresponding inner end of the member 23, which finger serves as a stop to maintain the toggle in its open position, as in Fig. 2, and prevent downward deflection. A like finger 30 10 is provided upon the outer end of the toggle member 24, and is adapted to extend over the corresponding outer end of the toggle member 23. In closing the storm sash, the toggle members are caused to extend upwardly as in Fig. 1, 15 and when the storm sash is completely closed, the pivotal points 22 and 25 are in axial alignment, as before stated. The toggle may then be rotated as a whole by means of the projecting end of the bolt 26, and brought into the lower 20 position indicated in Figs. 3 and 4, at which time, the finger 30 will lie to the outer side of the toggle member 23, so that the storm sash cannot be opened until after the toggle has been 25 reversely rotated to its upstanding position.
- This arrangement prevents the storm sash from being opened from the outside, and securely holds it against rattling.
- A stay bar 31 pivoted at one end to the toggle member 23, is provided upon its under edge with 30 one or more notches in the region of its free end, any one of which notches is adapted to take over the finger 30, when the storm sash is opened, and to so maintain the storm sash in a fixed opened position. The stay bar 31 is 35 adapted to be folded into parallelism between the toggle members, when the toggle is folded, as indicated in Fig. 4, when the storm sash is closed. A stop 32, projecting over the pivoted end of the stay bar, serves to restrain the said bar from 40 falling below its operative plane, as shown in Fig. 1. The free end of the stay bar 31 projects
- beyond the stop 11 and into the channel in which the upper sash of the window moves. By lowering this said upper sash until its bottom rail rests upon the inwardly projecting end of the stay bar 31, the storm sash will be held 80 securely in its partially opened position, thus affording excellent ventilation over the lowered upper sash, and effectively excluding rain, snow, or direct blasts of air. If the said upper sash be secured in its ventilating position, as described, the storm sash cannot be moved from the outside, with the result that entry through the window is prevented. This is a desirable 85 assurance when the rooms are used at night for sleeping purposes.
- When a change of season renders the continued use of the storm sash unnecessary, the latter may be detached by simply disengaging the studs 25 from the anchor plate 14, and unhooking at the connection 13. The storm sash 90 may then be stored, and again be as easily replaced in position, when the cold season approaches.
- Having thus described my invention, what I claim and desire to secure by Letters Patents of 100 the United States, is:
- A storm sash lock and regulator comprising a pair of links connected to form a toggle, pivot members for connecting the opposite ends of 105 said toggle to a storm sash and window frame respectively, said toggle being swingable about the axes of said members into and out of locking position when the storm sash is in closed position, an element on one of said links for coaction with said other link to secure said sash in closed 110 position when said toggle is swung into said locking position, and a stay bar on said other link for coaction with said element to retain the sash in a predetermined open position.
- JOHN CHRISTIAN.
